UNITED STATES PATENT OFFICE.

JOHN ANDERSON RUFFIN, OF NEW YORK, N. Y., ASSIGNOR TO THE HAMMOND TYPEWRITER COMPANY, OF NEW YORK, N. Y.

POLYCHROME-RIBBON ATTACHMENT FOR TYPE-WRITERS.

No. 846,026.

Specification of Letters Patent.

Patented March 5, 1907.

Application filed June 29, 1906. Serial No. 324,051.

To all whom it may concern:

Be it known that I, JOHN ANDERSON RUFFIN, a citizen of the United States, residing at New York city, New York, have invented certain new and useful Improvements in Polychrome-Ribbon Attachments for Type-Writers, of which the following is a specification.

My invention is a polychrome-ribbon attachment for type-writers, and I have shown it as applied to a machine of the well-known Hammond type.

The object of my invention is to provide a simple construction which will necessitate the employment of no additional parts to the machine over those now used.

In carrying out my invention I provide a type or ribbon shield of special construction having a plurality of openings for the passage of the hammer, the said shield, together with the ribbon-guide, being adjusted vertically in order to bring into play the different sections of the ribbon bearing the different colors.

The invention consists in the features and combination and arrangement of parts hereinafter described, and particularly pointed out in the claims.

In the accompanying drawings, Figure 1 is a plan view of the invention as embodied in a Hammond type-writer. Fig. 2 is a cross-sectional view of Fig. 1 substantially on the line 2-2, some of the parts being omitted. Fig. 3 is a view on the line 3-3 of Fig. 1, some of the parts being omitted; and Fig. 4 is a detail view looking from the right of the line 4-4, Fig. 1.

The anvil 1, the shuttle 2, and ribbon-spools 3 are of ordinary arrangement, as is also the hammer 1^x. The ribbon passes from the spool between the shuttle and the hammer by way of guide-fingers 4, 5, arranged in pairs on arms 6, which are pivoted to a suitable frame part at 7. The type or ribbon shield 8 is carried in the usual manner by arms 9 of curved form to embrace the anvil, the said arms being united at the front and pivoted to a bracket 10 on the ring or frame 11, surrounding the anvil.

As shown in Figs. 2 and 3, the shield is provided with two openings 12, vertically in line with each other and separated by the intact portion 13 of said shield. The polychrome ribbon is indicated in Figs. 2 and 3 at 14, the upper part being of any suitable color for

ordinary printing, such as black or purple, 55 while the lower portion is of a different color, such as red. These different color-sections of the ribbon pass in front of the two openings 12. For ordinary printing the parts are in such relation that the impression will be 60 made by the hammer striking through the upper opening 12 of the ribbon-shield to force the ribbon-section of ordinary color, together with the paper, against the type. When it is desired to print with the other color, such as 65 red, the ribbon-shield, together with the ribbon-guide, is raised, so as to bring the lower portion of the ribbon into the printing-plane and to bring the lower opening 12 of the type or ribbon shield into such position that the 70 hammer will operate therethrough. In order to effect this vertical adjustment of the type or ribbon shield and the ribbon-guide, I provide a finger-piece 15', connected with the arms 9 and formed by bending up at an inclination the rod or wire of which the said arms are formed. This finger-piece is located in front of the anvil within convenient reach of the operator, and by pressing thereupon the ribbon-shield arms are elevated to 80 raise the ribbon-shield, so as to bring the lower section of the ribbon into play. The upward movement of the ribbon-shield frame also raises the ribbon-guide frame or frames, for which purpose the arms 6 are provided with lugs or fingers 15, extending upwardly therefrom and reaching over the arms 9 of the type or ribbon shield frame. In order to hold the ribbon shield and guide in their elevated position while using the lower 90 section of the ribbon, I provide a catch 16 at the right of the anvil and having a rest at 17 for supporting the arm 9. The catch is carried by a post or arm 18, extending upwardly from a plate 19, which carries the alining-guide 20, the said plate being pivoted to the frame at 21, so as to be swung to one side, the amount of movement being determined by a screw 22, passing through a slot 23. The upper end of the post 18 is formed into a finger button or knob 24, and by pressing this toward the right the catch 16 is removed from over the arm 9, so that this may then be elevated by pressure upon the finger 15', and then upon releasing the catch 16 it will fly 105 back under the arm 9 of the ribbon-shield frame, so that the said arm will be supported in the rest 17 of the said catch. It is simply

necessary to release the finger piece or knob 24, when it will be carried to the left by a spring 25 at the pivot 21.

As before stated, when the type or ribbon shield frame is elevated it also elevates the ribbon-guides by means of contact of the arms 9 with the lugs or fingers 15.

In order to restore the parts to normal position for printing in the ordinary color, it is simply necessary to press the catch 16 toward the right by pressing upon the finger piece or button 24, so that the said catch will be removed from under the arm 9, whereupon the ribbon-shield, together with the guides, will drop down to their former position.

I have so constructed and arranged the parts that the type or ribbon shield may be elevated independently of the other parts, for which purpose it is simply necessary to press the arms 9 toward the left of Fig. 1 from under the lugs or fingers 15, and then the type or ribbon shield frame may be swung upwardly, and it may be held in its raised position by simply pressing it toward the right, whereupon the pivot portion 26 will slide in the slotted bearing 27 and will be retained by contact of the portion 28 with the wall 29 of said slot.

In order to limit the movement of the type or ribbon shield, together with the ribbon-guides, upwardly when changing from one ribbon-section to the other, I provide stops consisting of fingers 30 on the ribbon-guide arms 6, which stops abut against the under side of the frame.

It will be noticed from Fig. 2 that the arms 9 of the type or ribbon shield frame have a certain amount of lost movement before they strike the overlying lugs or fingers 15 of the ribbon-guide arms 6. This allows the ribbon-shield to have an excess of movement vertically in relation to the ribbon-guide and permits the openings 12 to be arranged, as indicated in the drawings.

In order to allow the operator to see the printing as it is being done, the ribbon-shield, together with the ribbon-guides, are normally in a lowered position, and means are provided whereby the said shield and guide are elevated to the printing-plane when the impression is to be made. This means consist of vertically-extending rods 31, the lower ends of which rest upon rollers 32 of the space-frame 33, arranged as is well-known in the Hammond machine. The upper ends of these rods 31 bear upon the under edges of the arms 6 of the ribbon-guides, and one of these arms carries a lug or finger 34 to bear on the under side of the ribbon-shield arm 9, and the other guide-arm 6, through its lug 15, performs a similar function to the lug 34 in elevating the other arm 9 of the ribbon-shield. Each time a key is depressed, therefore, the space-frame through the rods

31 will elevate the ribbon and the shield to cooperate with the other printing elements for making the impression, and when the key is released the ribbon and the shield will drop, so that the last letter printed will be clearly visible to the operator. It will be understood that the ribbon is vibrated only for its lower position.

I claim—

1. In combination in a type-writer with the shuttle and hammer, a ribbon-shield, a ribbon-guide and means for adjusting and holding the same vertically to various positions to bring differently-colored sections of the ribbon into use, substantially as described.

2. In combination, a ribbon-shield having a plurality of openings one above the other, a ribbon-guide and means for adjusting the shield and guide to different positions vertically to bring differently-colored sections of the ribbon into use, substantially as described.

3. In combination, a ribbon-shield, a movable support therefor, a ribbon-guide and means whereby the ribbon-guide is moved by the movement of the shield-support, said support and guide being separable from each other substantially as described.

4. In combination in a polychrome-ribbon attachment, a ribbon-shield, a frame carrying the ribbon-shield, ribbon-guide means and a catch for holding the shield-frame in an elevated position with means for imparting the movement of the said shield-frame to the guide means, substantially as described.

5. In a polychrome-ribbon attachment for type-writers, a ribbon-shield having a plurality of openings one above the other, a frame pivotally supported and carrying the said ribbon-shield, ribbon-guiding means with supports therefor, and means for transmitting the movement of the shield-frame to the guide means, substantially as described.

6. In combination the ribbon-shield, the frame pivotally supported, means for tilting the frame on its pivot, a catch for holding the frame in elevated position, said frame falling when released from said catch and ribbon-guide means to move with the ribbon-shield frame, substantially as described.

7. In combination a ribbon-shield, a frame pivotally supported and carrying the same, means for tilting the frame, a catch to engage the frame when elevated, the said frame dropping by gravity when the catch is swung aside, a ribbon-guide means moving with the said frame, substantially as described.

8. In combination, the ribbon-shield a frame carrying the same, guide means having a connection with the shield-frame, means whereby the shield and guide means may be adjusted to bring differently-colored portions of the ribbon into use, the said shield-frame being adapted to be disengaged from the

guide means to be elevated independently thereof, substantially as described.

9. In combination a ribbon-shield, a frame supporting the same, a catch for holding the frame in elevated position, guide means for the ribbon having a portion to engage the ribbon-shield frame, the said frame being adapted to be sprung aside to be disengaged from the guide means, substantially as described.

10. In combination a ribbon-shield frame pivotally supported, a ribbon-shield, guide means for the ribbon engaging a part of the ribbon-shield frame, the said ribbon-shield frame being adapted to be disengaged from the guide means and tilted upwardly on its pivot and means for holding the ribbon-shield frame in its tilted position, substantially as described.

11. In combination a ribbon - shield, a frame pivotally supported, a pivot-bearing for the said frame having a notch or slot therein, guide means engaging the ribbon-

shield frame, said ribbon-shield frame being detachable from the guide means by pressing it aside and being sustained in elevated position by moving its pivot portion in the slotted bearing, substantially as described.

12. In combination in a type-writer, a frame pivotally supported, a pivot-bearing therefor and means whereby the frame is held in a tilted position by pressing the said frame laterally, substantially as described.

13. In combination a ribbon - shield, a frame carrying the same movably supported, 35 catch means to engage under the frame, the said catch being carried by the alining guide-support, a ribbon-guide and means for connecting the ribbon-guide with the ribbon-shield arm, substantially as described. 40

In testimony whereof I affix my signature in presence of two witnesses.
